UNITED STATES PATENT OFFICE

2,131,564

RELEASEABLE HOLDING ARM FOR DOORS
AND THE LIKEDavid R. Lasier, Chicago, Ill., assignor to Norton
Lasier Company, Chicago, Ill., a corporation of
Illinois

Application June 7, 1937, Serial No. 146,729

3 Claims. (Cl. 189—49)

This invention relates to an improved holding device for doors of the type having an automatic release for rendering the holding means ineffective when exposed to heat such as that occasioned by a fire whereby the door may be free to close and automatically to cut off drafts and the communication between rooms so as to prevent or deter the spreading of the fire. The releasing means may depend for its action upon a fusible element or link of well known construction which will fuse at a predetermined temperature.

It is an object of the present invention to provide a holding device for doors or the like, which may be used separately or in conjunction with checking and closing mechanism which will effectively hold the door or the like, in any desired open position, according to the adjustment of the holding means, and which will readily and quickly release the door upon the subjection of the device to a predetermined temperature, whereby the door will at once be free to close, as for instance, under the influence of closing spring or equivalent mechanism.

It is a further object of this invention to provide a releasable holding device of the above described type which is very simple in construction and is thus easily and cheaply manufactured and yet which is highly efficient, durable and dependable in service.

These and other objects not specifically enumerated will readily appear to one skilled in the art as the following description proceeds which may be more readily understood if considered in the light of the accompanying drawings in which:

Figure 1 is a plan view of a door closing and checking device of the surface type equipped with a holding arm constructed in accordance with this invention;

Figure 2 is an elevational view of the device shown in Figure 1;

Figure 3 is an enlarged perspective view of a holding arm constructed in accordance with this invention;

Figure 4 is an enlarged perspective view of a portion of one of the arms showing the construction of the friction head and releasing means therefor;

Figure 5 is a plan view of the mechanism shown in Figure 4;

Figures 6 and 7 are cross sectional elevational views taken on the line 6—7 of Figure 5 and looking in the direction of the arrows. Figure 6 shows the pin in an inward position with the

friction head raised, whereas Figure 7 shows the pin outward with the friction head lowered;

Figure 8 is an elevational view in cross section taken on the line 8—8 of Figure 5, and looking in the direction of the arrows.

By referring to the drawings it will be noted that the invention is here illustrated as embodied in a holding arm which consists of a crank arm 10 and a forearm 11, the first of which is connected at one end 12 to the spindle 13, of a door 10 closing and checking device 14. The checking device forms no part of this invention and may be of any suitable type or omitted altogether. The device here illustrated is the usual surface type door check and is connected by means of 15 a bracket 15 to the upper surface of the door 16 so as to be carried thereby when the door is moved to open position on the hinges 17.

The outer end of the crank arm 10 is provided with a friction head 18 having a central 20 bearing opening 19 and a spiral friction face 20. The crank arm above described is of substantially the same construction as that constituting the holding device disclosed in applicant's Patent No. 1,826,553 of October 6, 1931, 25 where it will be noted in Figure 10, the spiral face of the friction head has a gradual taper and an abrupt step between the high and low portions of the spiral.

The forearm in the illustrated embodiment of 30 the invention is made up of four separate parts so as to provide for an adjustment as to length and angularity in mounting and to permit the attachment thereof in different horizontal planes. The outer end consists of a frictional 35 head 21 pivoted as by a pin 22 to the socket member 23 equipped with a set screw 24. The rod 25 is retained in the member 23 in any desired adjusted position by the holding action of the set screw and has provided at its other end, a universal joint 26 having horizontal and vertical 40 pivots for connecting the same to the bracket 27. As shown in Figures 1 and 2, this bracket is attached to the door frame by means of screws 45

28. The above described features of the forearm are substantially the same as those illustrated in applicant's Patent No. 1,826,553 above referred to and thus the forearm is capable of acting in substantially the same way, it being understood that the friction head on the outer 50 end is provided with a frictional face adapted to have cooperative engagement with the frictional face on the head 18 of the crank arm.

The novelty of this invention resides in certain structural features which are best illustrated 55

in Figures 4 to 8 inclusive. By referring to Figure 4 it will be noted that the friction head 21 on the end of the forearm has a spiral face made up of two parts, first a lower and integrally formed part 30, and secondly, the upper and separable part 31. The friction surface of part 31 is somewhat above that which would constitute a continuation of the spiral surface of the lower part 30, and the part itself is formed as a separate piece movably held on the head by means of dowel pins 32 or other similar means. These pins fit relatively loosely either in the piece 31 or in the head itself so that the friction part 31 is free to be lifted and lowered under the cam action of a pin, hereinafter described. It will be noted that the spiral face of the head 21 has a step between its high and low portions and therefore provides a friction head corresponding in shape and adapted for cooperation with the friction head on the crank arm. Due to the fact that the movable part 31 is slightly higher than the projected incline of the lower portion, it alone serves as the frictional binding surface, the lower part 30 being cut away so as to avoid frictional contact with the friction head of the crank arm.

The head shown in Figure 4 is provided with a central opening 33 which preferably has flattened sides 34 so as to have a non-rotating fit 30 with the bolt 35 as shown in Figure 8. The bolt is preferably provided with a head 36, and a round bearing portion 37 which fits into the round hole 19 of the friction head of the crank arm. The bolt also extends into the head 21 35 and has flattened surfaces 38 to engage with the flat sides 33 of the head. The bolt further projects beyond the head 21 and is provided with a threaded end 39 for receiving a nut 40. A washer 41 may be placed under the head 36 of the bolt.

It is apparent from an understanding of the above construction that the nut 40 may be adjusted to any desired position so as to vary the space between the friction face of the head 21 45 and the under surface of the head of the bolt so as to provide a binding between the friction surfaces of the heads at various angular positions according to the requirements of a particular installation. In this respect, the device behaves similar to that shown in the applicant's Patent No. 1,826,553, above referred to. When the parts have been brought to the angular position at which the binding action will occur the frictional faces will be wedged together and exert a holding action resisting the normal tendency for the door to close, as for instance, under the influence of a closing spring of a door closing device. However, if it is desired to close the door the same may be effected manually by exerting 50 a closing pressure on the door sufficient to overcome the frictional resistance of the holding device. After the frictional engagement of the spiral faces has been broken the arms will pivot freely and the door will be free to close, the same as if no holding device was present.

The structural features of this device which provide for the automatic release will now be described. With particular reference to Figures 4 to 8 inclusive, it will be noted that the head 18 is provided with a laterally extending hole 45 which is adapted to receive a pin 46. The pin has a sliding fit in the hole and is so designed that under ordinary circumstances when the device is adjusted for holding action 75 it is contained entirely within the hole with its

outer end substantially flush with the outer surface of the crank arm as shown in Figure 6. Adjacent the hole, a holding stud or screw 47 is provided which serves as a mounting for a latching member 48. The latching member is provided at its end with a fork, or a pair of spaced fingers 49 which straddle the stud of the screw 47. The latching member is also preferably provided with a spring member 50 held by means of a screw 51 and providing a projecting end 52 10 serving as a means for holding the fusible link 53. Also carried by the head 21 is a stationary pin 54, extending outwardly in a manner to form a holder for the other end of the fusible link 53. The pin 54 may be mounted by means of screw 15 threads 55 and is equipped with a notch 56 for holding the fusible link against displacement. The pin 54 and the spring 50 of the latching member are preferably so located with respect to the length of the fusible link that the link 20 when inserted in position, places the spring 50 under slight tension. The fusible link thus holds the latching member in position against the side of the head 21 and over the end of the pin 46, as shown in Figure 6.

The sliding pin 46 as shown in Figures 4 to 7 inclusive, is provided with a notch on its upper surface having an inclined cam face 60. The friction part 31 as shown in Figure 4 which is movably mounted is provided with a downwardly 30 extending lug 61 having cooperating engagement with the cam face 60 on the pin. The cam face 60 on the pin is so disposed with respect to the length of the pin that when the pin is inwardly, as shown in Figure 6 and as maintained by the 35 latching member, the cam face 62 on the lug 61 is held on the upper portion of the incline and serves as a support for maintaining the friction part 31 in an elevated position. It is this part 40 31 in its elevated position that provides the holding means under normal conditions and consequently it is with the parts in this arrangement that the holding adjustment is made.

It should be further understood that the cam faces 60 and 62 are of such inclination that when the pin 46 is released by means of the removal 45 of the latching member 48, the pressure exerted on the frictional member 31 when the faces are holding, will cam the pin outwardly to the position shown in Figure 7 and thus provide an increased space such that the frictional holding action is at once broken and the door is released.

Accordingly, it will be seen that by this invention the fusible link which is of usual construction, serves to hold the latching member 48 55 in position between the pin 54 and the holding screw 47 and that the latching member, while in such position, maintains the sliding pin 46 inwardly so that the semiannular frictional face member 31 is supported in an elevated position 60 by means of the cam faces 60 and 62 on the pin and lug 61, respectively; that in such position the holding device may be adjusted to provide a frictional binding action at any desired angular position so that the door or similar member, upon a predetermined degree of opening movement, is held in the selected position; and further, that when it is desired to close the door, the frictional holding means may be released by exerting manually, a closing pressure on the door 70 sufficient to break the frictional engagement between the friction heads or that on the other hand, the same may be automatically released by a fusion of the fusible link 53.

It is well understood that links of this type are 75

made in two parts and will release upon being subjected to a heat such as encountered by fire. Upon fusion of the link 53, it will be seen that the latching member 48 will no longer be held by the 5 pin 54 and that the same by its own gravity, will swing downwardly and fall to the floor or away from its position over the end of the pin 46. Then, immediately upon freeing the pin 46, the cam action of the faces 60 and 62 will cause the pin to 10 move outwardly and to thereby lower the friction part 31 and relieve the binding action between the friction head 21 and the cooperating head 18 of the crank arm.

I claim:

- 15 1. A pair of arms having spirally disposed cooperating frictional faces, said arms being pivot- ed adjacent said faces whereby said faces are adapted to bind and hold said arms when in pre- determined relative positions, the spirally dis- 20 posed face on one of said arms being provided on a separate part displaceable axially of said pivot, a pin mounted in the corresponding arm having a cam surface in supporting engagement with said displaceable part, said pin being mov- 25 able for imparting to and receiving movement from said displaceable part, a latching means for holding said pin against displacement and a fus- sible link for said latching means.
- 20 2. A holding device of the character described comprising a crank arm and a forearm and a 25 pivotal connection therebetween, said forearm having a displaceable member provided with a spirally disposed frictional surface and said crank arm having a spirally disposed frictional face for cooperative engagement with the spiral face of 30 said displaceable member, said displaceable mem- ber having a cam surface, a pin having a corre- sponding cam surface in engagement with said first-named cam surface and serving to support said displaceable member in one position to dis- place the same for releasing the binding action of said spiral face in another position, a latching member carried by said arm for holding said pin and a fusible link for holding said latching mem- 35 ber against displacement through the instrumen- tality of a spring member.

spirally disposed frictional surface and said crank arm having a spirally disposed frictional face for cooperative engagement with the spiral face of said displaceable member, said displaceable mem- 5 ber having a cam surface, a pin having a corre- sponding cam surface in engagement with said first-named cam surface and serving to support said displaceable member in one position but to displace the same for releasing the binding action of said spiral face in another position, a 10 latching member carried by said arm for holding said pin and a fusible link for holding said latch- ing member against displacement.

3. A holding device of the character described comprising a crank arm and a forearm and a 15 pivotal connection therebetween, said forearm having a displaceable member provided with a spirally disposed frictional surface and said crank arm having a spirally disposed frictional face for cooperative engagement with the spiral face of 20 said displaceable member, said displaceable mem- ber having a cam surface, a pin having a corre- sponding cam surface in engagement with said first-named cam surface and serving to support said displaceable member in one position to dis- 25 place the same for releasing the binding action of said spiral face in another position, a latching member carried by said arm for holding said pin and a fusible link for holding said latching mem- 30 ber against displacement through the instrumen- tality of a spring member.

DAVID R. LASIER.
